UNITED STATES PATENT OFFICE.

CLARENCE S. HILL, OF ILION, NEW YORK.

VACUUM-CLEANER NOZZLE.

1,109,069.

Specification of Letters Patent.

Patented Sept. 1, 1914.

Application filed June 10, 1911. Serial No. 632,359.

To all whom it may concern:

Be it known that I, CLARENCE S. HILL, of Ilion, in the county of Herkimer and State of New York, have invented certain new and 5 useful Improvements in Vacuum-Cleaner Nozzles; and I do hereby declare that the following is a full, clear, and exact description thereof, which will enable others skilled in the art to which it appertains to make 10 and use the same, reference being had to the accompanying drawings, and to the reference-numerals marked thereon, which form part of this specification.

The purpose of my invention is to provide 15 an improved nozzle for vacuum cleaners which will have certain advantages of construction and operation resulting in great efficiency in a variety of ways as will hereinafter appear.

20 My invention relates to that class of nozzles wherein the body or nozzle proper rests flat upon the floor or other surface being cleaned and the air is exhausted from the body through a hollow handle pivotally connected to the body.

25 One object of my invention is to provide an improved joint between the handle and the body member and especially to make said joint spring tensioned so that it may be 30 easily operated, and permanently and self-adjustingly air tight in any position and in spite of usual wear upon the contact surfaces of the joint.

35 A further object is to provide an improved agitator that will automatically project from the nozzle slot to a degree varying according to the surface being cleaned.

40 Another object is to provide a means near the slot into which small objects may readily slide from the surface being cleaned and be retained if too heavy to be carried farther by the suction.

45 A further object of my invention is to provide a jointed nozzle wherein the handle can be moved to an angle considerably less than a straight angle relative to the bottom of the body and a locking device for holding it in such position. This position is very useful in cleaning the tops of windows and door casings and moldings and similar ledges.

Figure 1 is a plan view of a nozzle embodying my invention. Fig. 2 is a side elevation of the same. Fig. 3 is a cross-sectional view on line 3—3 of Fig. 4, and Fig. 4 is a perpendicular sectional view on line 55 4—4 of Fig. 3. Fig. 5 is a perpendicular sectional view on line 5—5 of Fig. 4. Fig. 6 is a perspective view of the joint end of the handle. Fig. 7 is a side elevation of the sliding retaining plate 25. Fig. 8 is a pattern view of the apertured bearing 18 before it is bent to its semi-circular form.

Referring to the drawings in a detailed description, my nozzle has a hollow body 10 consisting of bottom 11, top 12, sides 13 and 65 provided with a nozzle slot 14 in the bottom near its forward edge. The body 10 is preferably wider and thinner toward its front in the usual shape of such nozzles so as to give sufficient length to the slot 14. Toward the 70 rear the body 10 is drawn together to form a hood or socket 15 into which fits the cylindrical head 16 on the end of the hollow handle 17 to form a socket joint between the handle 17 and the body 10. The axis of the 75 head 16 is arranged horizontally so as to allow the handle 17 to be moved up and down to the desired angle relative to the floor or other surface being cleaned. The socket 15 is provided with a semi-cylindrical 80 apertured bearing 18 of which the side portions 19 are secured by air tight joints to the sides 13 of the body while the top 20 and bottom 21 of the bearing 18 are secured to the top 12 and bottom 11 of the body respectively by air tight joints. An aperture 85 22 through the head 16 completes the passage for the air and dust to pass up from the body 10 through the aperture 23 in the bearing 18 and the aperture 22 in the head 90 16 to the hollow handle. It is understood that the suction is communicated to the hollow handle 17 by suitable connections with a pump or fan or other vacuum producing means. (Not shown). The aperture 23 in the bearing 18 extends substantially from the top 12 of the body to the bottom 11 while the aperture 22 in the head is not so wide and is so placed that whatever the angle of the handle it will communicate with the 100

aperture 23 and not pass above the top 20 of the bearing 18 nor below the bottom 21 of the bearing.

After forming the ends of the socket 15 the sides 13 extend rearwardly and are provided with rollers 24 suitably mounted and arranged thereon so as to support the body 10 in proper position on the floor or other surface and to allow of the nozzle being easily moved over such surface and yet not prevent the handle 17 from being swung down between and below said extended sides 13 to a position at less than a straight angle with reference to the bottom 11 of the body 15 of the nozzle as indicated in dotted lines in Figs. 2 and 4, which I will call depressed position. Upon the inner sides of the extended sides 13 are slidably located retaining plates 25 having their forward edges 25^a formed in a curve fitting against the rearward side of the head 16 adjacent to its ends and extending nearly half way around said head. Projecting through horizontal slots 26 in the extended sides 13 and into the retaining plates 25 there are screws 27 preferably having double-stepped heads the first step of which 27^a is larger than the width of the slots 26 and so holds the plates 25 slidably against the sides 13. Over the first step and held thereon by the larger outside step 27^b of the screw head is secured one end of a bent spring 28 the other end of which is secured to a screw 29 fastened into the side 13 toward the body 10. The tension of these springs 28 is such as to draw the sliding plates 25 snugly against the head 16 and so keep that member of the joint in the necessary close contact with the socket 15 and bearing 18 so as to make the joint substantially air tight and to keep it such even upon considerable wear of the contact surfaces.

The screws 29 preferably extend through the side 13 into recesses 30 centrally located in the ends of the head 16. These recesses are larger than the projecting ends of the screws 29 which therefore do not normally come into contact with the head 16 but serve as supplementary securing devices during assembling of the nozzle or in case one or both of the retaining plates 25 should accidentally become displaced.

Toward the rear of each of the plates 25 and upon their inner sides, that is their sides toward each other and toward the handle 17, is provided a projecting lug 31 having its end toward the body 10 concave and provided with ratchet teeth 31^a preferably having their upper faces 31^b slanting downwardly and their lower faces 31^c straight. Upon each side of the handle 17 are located projecting ears 32 having their rearward faces formed as arcs having their

centers at the axis of the head 16 and having ratchet teeth 32^a on said arcs with the upper faces 32^b of the teeth straight and the lower faces 32^c slanting upwardly. The ears 32 and lugs 31 are so located and arranged that as the handle is turned down to an angle approaching a straight angle with reference to the bottom of the body 10, the slanting faces 31^b of the ratchet teeth 31^a on the lugs 31 will come into camming engagement with the slanting faces 32^b upon the ratchet-teeth of the ears 32 and upon sufficient downward pressure being applied to the handle 17 the lugs 31 will be cammed back against the tension of the springs 28 sufficiently to allow the ratchet teeth 32^a to ride over the teeth 31^a and the return of the handle 17 to upward position will be prevented by the engagement of the straight sides 32^c and 31^c of these teeth. It will be obvious that the relative arrangement of the toothed lugs 31 and toothed arc-shaped ears 32 is such that the handle may be moved into this locked condition at various angles ranging from a middle position at a little more than a straight angle with reference to the bottom of the body 10 to an angle considerably less than a straight angle. This latter or depressed position is indicated in dotted lines in Figs. 2 and 4, and enables the operator to use my nozzle upon the upper edges of window or door casings or similar ledges, which work could not be conveniently done unless the handle could be moved into said depressed position and locked therein. When the handle is locked in any of what I have called the middle positions, my nozzle may be used for cleaning surfaces that do not allow a sufficient support for the rollers 24, such for instance as curtains, draperies, radiators, the sides or legs of furniture or upholstered surfaces.

When it is desired to move the handle from a locked position to a more upward locked position or to the upward freely moving position a backward pressure is applied to the heads of the screws 27 until the toothed lugs 31 are out of engagement with the ears 32 when the handle may be readily raised to desired position. When the handle is in the upward position indicated in full lines in Figs. 2 and 4 it can be freely moved through a considerable arc and so accommodate itself to the different work to be done or to the size of the operator and allows for a slight movement at each forward and backward stroke which keeps the nozzle slot at proper working position at all parts of the stroke.

As a convenient means of assisting in slidingly supporting the plates 25, slots 33 are provided at the rear end of the plates 25 into which slidably fit projections 39 from the extended sides 13. These projections 39

may conveniently be the inner ends of the pivots 40 upon which are mounted the supporting rollers 24. Extending longitudinally across the nozzle slot 14, and yieldingly 5 projected slightly therethrough is an agitator 33 which serves to stir up the dust opposite the slot and to move the nap or projecting loose fiber of the surface being cleaned which allows the suction to more 10 effectively gather up all the dust. By having the agitator yieldingly instead of rigidly projecting through the slot, I find that it is much more effective as an agitator as it adjusts itself to the varying character of the 15 surfaces being cleaned, thereby loosening a maximum amount of dust and allowing a minimum of air to pass into the slot without carrying dust with it. When operated upon a hard smooth surface the spring agitator is almost entirely forced back into the slot by reason of the hardness of such surface and so does not raise the slot too far from the surface being cleaned for effective suction but in this position the agitator being 20 under tension is stiffer and stronger and so more effective against such surfaces as closely woven carpets, rugs or matting. When the nozzle is used upon softer fabrics such as carpets having long pile or loose or 25 projecting parts the spring agitator not being under so great tension extends farther from the slot into such soft materials but is not so stiff in its contact and therefore does not damage the materials or substance being cleaned.

Preferably I form the spring tensioned agitator out of spring wire bent in the form of a loop 34 at each end to provide means for yieldingly securing the agitator to the interior of the body 10. The extreme ends 34^a of the loops 34 are secured to the body while the balance of the loop forms a yielding spring to keep the main length of the wire which is the agitator itself in desired position. It will be noted that the agitator itself aside from the resiliency of the loops 34 is resilient and so capable of yielding to local pressure or inequalities in the surface being cleaned. The rounding shape of the agitator keeps it from digging into the surface being cleaned or from itself being caught by slivers, tacks or other projections. Just back of the rear edge of the slot 14 is a block 35 having a gently rising surface 36 sloping upward from the rear edge of the slot 14, and then giving way to an abrupt decline 37. A pocket is thus formed into which small heavy articles such as pins, needles, buttons, etc., may fall and be retained when too large and heavy to be drawn up into the handle by the suction. The gentle slope of the surface 36 and its arrangement with reference to the slot 14

allows these small articles to be readily picked up by the suction combined with the 65 scooping action of this surface 36 as the nozzle is shoved forward.

What I claim as new and desire to secure by Letters Patent is:

1. In a vacuum cleaner nozzle a hollow 70 body with a nozzle slot therein adapted to engage the surface to be cleaned, a handle pivotally connected to said body and swinging freely thereon at certain angles, toothed racks upon said body and upon said handle 75 adapted to be brought into engagement with each other at other angles, one of said toothed racks being movably mounted to be withdrawn from engagement with the other, and resilient means for normally extending 80 said movable toothed rack into the path of the other.

2. In a vacuum cleaner nozzle a hollow body having a nozzle slot on its lower side, 85 a handle pivotally connected to said body, supports on said body on each side of said handle extending rearwardly of the pivoting point of said handle and body and adapted to support said body in operative position upon the surface being cleaned 90 while the handle is above said supports and to allow said handle to be swung therebetween and means for detachably locking said handle in said lowered position.

3. In a vacuum cleaner nozzle a hollow 95 body having a nozzle slot on its lower side, a handle pivotally connected to said body, supports on said body on each side of said handle, extending rearwardly of the pivoting point of said handle and body and 100 adapted to support said body in operative position upon the surface being cleaned while the handle is above said supports and to allow said handle to be swung therebetween and toothed members upon said handle and said supports adapted to engage 105 each other and lock said handle in said lowered position.

4. In a vacuum cleaner nozzle a hollow 110 body having a nozzle slot on its lower side, a handle pivotally connected to said body, supports on said body on each side of said handle extending rearwardly of the pivoting point of said handle and body and adapted to support said body in operative 115 position upon the surface being cleaned while the handle is above said supports and to allow said handle to be swung therebetween and past said supports and toothed members upon said handle and said supports adapted to engage each other and lock 120 said handle in said lowered position.

5. The combination in a vacuum cleaner nozzle of a hollow body with a nozzle slot therein and an agitator consisting of a resilient wire formed in a loop having its ends 125

secured to said body and its loop extending longitudinally of said nozzle slot and yieldingly projecting therethrough.

6. The combination in a vacuum cleaner
5 nozzle of a hollow body with a nozzle slot
therein and an agitator consisting of a re-
silient wire having its central portion ex-
tending longitudinally of said slot and its
10 ends bent to one side of said slot and fas-
tened at their extremities to said body and

adapted to yieldingly project the central portion of said wire through said slot.

In witness whereof I have affixed my signature, in the presence of two witnesses, this 3rd day of June, 1911.

CLARENCE S. HILL.
